Primary Examiner — Catherine S Posthauer

(74) Attorney, Agent, or Firm — Stephen J. Weyer, Esq.;
Stites & Harbison, PLLC(57) **CLAIM**

The ornamental design for a bottle, as shown and described.

DESCRIPTION

FIG. 1 is a top, front and right side perspective view of a bottle, showing my new design;

FIG. 2 is a front elevation view thereof;

FIG. 3 is a rear elevation view thereof;

FIG. 4 is a left view thereof;

FIG. 5 is a right side view image thereof; and,

FIG. 6 is a top plan view thereof.

Elements drawn in broken lines represent environmental elements that form no part of the claimed design.
